LOCK DEVICE

Edward N. Jacobi, Milwaukee, Wis., assignor to
 Briggs & Stratton Corporation, Milwaukee,
 Wis., a corporation of Delaware

Application September 5, 1941, Serial No. 409,611

3 Claims. (Cl. 70—81)

This invention relates to locks and refers particularly to door latch locks of the type shown in Patent No. 2,208,003, issued to E. N. Jacobi, July 16, 1940.

Lock devices of this character have a toggle type latch bolt biased to its operative keeper engaging position and adapted to snap in back of a keeper or striker when the door on which the lock device is mounted is slammed shut. This spring biased toggle bolt is retractable by inward depression of a lock cylinder which, however, must be in its unlocked position of rotation to permit depression.

With the cylinder secured in its locked position of rotation from which it can be turned only through use of the proper key, the toggle bolt theoretically could not be retracted. However, in practice it was found that vibration sometimes shook the bolt down to its retracted position and allowed the door to open, and sometimes in closing the spring biasing the bolt to its operative keeper engaging position would not overcome the friction retarding movement of the bolt to this position, and as a consequence, the bolt would not be moved to its fully operative keeper engaging position.

To overcome these disadvantages, the present invention has as one of its objects the provision of means for positively preventing retraction of the bolt when the cylinder is in its locked position of rotation.

Another object of this invention is to provide cooperating means on the toggle bolt and the cylinder whereby rotation of the cylinder to its locked position positively moves the toggle bolt to its operative keeper engaging position in the event its spring has not already done so, and thereafter secures the bolt against retraction.

With the free bolt type of lock construction heretofore in use, it was possible to turn the lock cylinder to its locked position while the compartment door was open, unthinkingly remove the key, and throw it into the compartment, and then slam the door. This is especially bad when the same key is also the car key, and it is, therefore, a further object of this invention to so interlock the bolt and cylinder that this objectionable situation could not arise.

In other words, the cooperating means on the bolt and cylinder by which retraction of the bolt is positively prevented when the cylinder is in its locked position of rotation precludes slamming the door shut with the cylinder turned to its locked position.

In lock devices of the type here under consideration, as well as in other tumbler locks, it is desirable that the cylinder be removable. Various devices have been employed in the past for removably securing the cylinder in its casing, but in general they all embody a spring

pressed detent carried either by the cylinder or the casing and extending across the juncture therebetween to engage with an abutment or shoulder from which the detent must be freed to permit withdrawal of the cylinder.

It is also the practice in tumbler locks of the character described to retain the individual tumbler springs either by individual retainers or more suitably by means of a single retainer fixed to the cylinder with portions thereof disposed over the tumbler springs.

With a view toward minimizing the number of parts, the present invention has as another of its objects the provision of a novel manner of combining the functions of retaining the tumbler springs and removably holding the cylinder in its casing.

To this end, it is an object of this invention to provide a novel combined tumbler spring retainer and cylinder retaining member so designed and assembled with the cylinder that the reaction of the tumbler springs holds this combined retainer in an operative position projecting a lug or lip thereon beyond the wall of the cylinder for engagement with a retaining shoulder in the bore in the casing.

More specifically, it is an object of this invention to provide a combined tumbler spring retainer and cylinder retaining member which consists of a stamping set into a recess in the cylinder wall in such a manner that it may be considered to be floatingly disposed and biased to a position projecting its stop lug or lip beyond the cylinder wall by the reaction of the tumbler springs.

Another object of this invention is to simplify the construction of the individual tumblers.

Still another object of this invention resides in the provision of a novel cap for the end of the casing which is formed as a die casting and incorporates as an integral part thereof a protective boss projecting forwardly to partially embrace the protruding end of the cylinder and thereby prevent access to the combined tumbler spring and cylinder retainer in the locked position of the cylinder.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a longitudinal sectional view through a lock device constructed in accordance with this invention;

Figure 2 is a cross sectional view taken through Figure 1 on the plane of the line 2—2;

Figure 3 is a perspective view of the lock casing per se;

Figure 4 is a perspective view of the combined casing cap and bolt retainer;

Figure 5 is a perspective view of the cylinder;

Figure 6 is a perspective view of the combined tumbler spring and cylinder retainer; and

Figure 7 is a perspective view of one of the tumblers.

Referring now particularly to the accompanying drawings, in which like numerals indicate like parts, the numeral 5 designates the door of a glove compartment, only the upper wall 6 of which is shown.

Extending down from the upper wall 6 directly adjacent to the door frame is a striker plate or keeper 7 behind which a toggle-like latch bolt 8 carried by the lock device indicated generally by the numeral 9 engages to secure the compartment door 5 closed. The lock device 9 is mounted on the door so that when the door is closed, the latch bolt automatically engages behind the striker plate or keeper.

The lock device comprises a casing 10 preferably formed as a die casting and having a bore 11 to slidably and rotatably receive a lock cylinder 12. A longitudinal slot 13 through the top wall of the casing accommodates the latch bolt 8. The sides of this slot 13 are longitudinally grooved as at 14 to receive trunnions 15 formed as integral parts of the toggle-like latch bolt. These trunnions are held against the inner ends of the grooves 14 by spaced arms 16 projecting rearwardly from and constituting an integral part of a latch bolt retainer 17.

This latch retainer, like the casing, is preferably a die casting and has an annular part 18 from which the arms 16 project. The annular part fits over the front end of the casing where it is clinched in place. The latch retainer thus defines the mouth of the bore in which the cylinder is received with its front end protruding therefrom to project from the front face of the door panel as a push button.

The cylinder is also preferably die cast and has an open transverse tumbler cavity 19 communicating with a longitudinal keyway 20. The side walls of the cavity have opposite grooves 21 extending across their full width to provide tumbler guideways in which the side edges of tumblers 22 are slidably received.

At one edge of the cavity the cylinder is formed with bridges 23 which extend across the cavity between the tumbler guiding grooves 21. These bridges, together with a similarly located ledge (not shown) on the inner or rear end of the cavity provide lands in position to collide with spring rests 24 on the tumblers to limit the stroke of the tumblers under action of their springs 25.

The individual tumblers, as best shown in Figure 7, are stamped from flat band stock and have their medial portions recessed or cut out at one edge to provide a key opening 26. The spring rests 24 are projections formed on the inner edges of the intermediate portions of the tumblers bent back onto the intermediate portions as clearly shown so as to dispose the actual spring seats in line with the intermediate portions. The spring seats are pointed to enter the ends of the

coil springs and prevent displacement of the springs.

Heretofore, the tumbler springs were held in place either by individual retainers or a common retainer secured in the cylinder, but in all instances in the past, the tumbler spring retainers were fixed and generally were staked into the cylinder.

With the present invention, an entirely new form of tumbler spring retainer is employed, and as a result the functions of retaining the individual tumbler springs and also removably securing the cylinder in the casing bore are performed by one unit. For this purpose, a novel combination tumbler spring and cylinder retainer indicated generally by the numeral 27 is provided.

As best shown in Figure 6, this retainer 27 consists of a sheet metal stamping having an elongated bar or strip 28 of a length greater than that of the tumbler cavity and having a plurality of spring seats 29 formed thereon. These spring seats may be roughly defined as teeth bent laterally from one edge of the bar 28 and to guard against displacement of the ends of the springs from these seats, their extremities are bent inwardly as at 30.

To accommodate the retainer 27, the cylinder has an open slot 31 extending along one side of the tumbler cavity and continuing past the front end thereof. This slot receives the flat bar or strip 28 with the front end portion thereof located forwardly of the tumbler cavity.

At its rear end, the strip 28 has a projection 32 which enters a hole 33 in the inner end portion of the cylinder which closes the rear or inner end of the tumbler cavity. In this position the retainer 27 has its spring seats 29 disposed over the individual tumbler springs and as will be readily apparent, is free to swing on the fulcrum provided by the engagement of the projection 32 in the hole 33.

The retainer is thus substantially floatingly mounted and is free to move toward and from the surface of the cylinder in a direction substantially along the line of thrust of the tumbler springs and as will be obvious the reaction of the tumbler springs tends to swing the retainer outwardly of the cylinder.

This outward motion of the retainer is limited by the engagement of its front end 34 with the inner face of a cylindrical cap 35 pressed onto the front end of the cylinder.

At its front end portion which lies forwardly of the tumbler cavity, the retainer has a transverse arm 36 extending laterally in the same direction as spring seats 29, and at its extremity the transverse arm is bent down to form a flat portion 37 parallel with the bar and provided with an extension 38 which lies directly opposite the front end portion 34.

This extension 38 like the end portion 34 is engageable with the inner surface of the cap 35, and to guard against binding, the edges of the end portion 34 and the extension 38 which engage the cap lie in a plane normal to the plane of the bar or strip 28, and the location of the retainer is such that these edges engage the cap at points equidistant from a median longitudinal plane passing through the axis of the cylinder and parallel with the plane of the bar or strip 28.

On the rear edge of the transverse arm 36 is an outwardly bent lip 39. This lip, in the free position of the retainer, projects beyond the surface of the cylinder to be engageable behind a shoulder 40 on the latch retainer 17 to thereby

removably hold the cylinder in the casing bore. In assembling the cylinder with the casing the lip 39 on the spring pressed retainer is cammed in over the edge of the shoulder 40 by a cam surface 41 formed at the junction of the face of the annular part 18 with the cylindrical surface 42 of a boss 43 protruding from the front of the latch retainer 17. The cylindrical surface 42 is concentric with the bore and is somewhat larger in diameter than the bore which allows for the annular chamfer which forms the cam surface 41.

As clearly shown in Figure 4, the boss extends around only a portion of the mouth of the bore and is in position to cover the exposed arm 36 of the retainer 27 in the locked position of rotation of the cylinder. Hence, the retainer 27 cannot be depressed to disengage its lip 39 from the shoulder 40 until the cylinder is turned to its unlocked position whereupon the exposed arm 36 is clear of the boss 43.

Moreover, even though through deft manipulation it would be possible to depress the free end of the retainer 27 to disengage its lip 39 from the shoulder, removal of the cylinder could not be effected in the locked position of rotation as the projecting ends of its tumblers would collide with the back of the annular part of the latch retainer 17.

Rotation of the cylinder is limited to 90° by the complementary shape of the inner end of the cylinder and the bottom of the casing bore.

Also by virtue of the relative shape of the inner end of the cylinder and the bottom of the bore, the cylinder cannot be depressed in the fashion of a push button in its locked position of rotation. It must be turned to its unlocked position and when so turned the cylinder may be depressed to rock the toggle bolt on its trunnions and retract the same from engagement with the keeper or striker plate 7.

As in the patent hereinbefore mentioned, the bolt is biased to its operative keeper engaging position by a spring 44. This spring presses the inner arm 45 of the bolt against the end of the cylinder and thus pushes the cylinder forwardly to hold the lip 39 firmly against the shoulder 40.

Attention is directed to the fact that the location of the fulcrum about which the retainer 27 swings lies inwardly, that is, closer to the axis of the cylinder than the lip 39. Pressure on the lip 39 resulting from its engagement with the shoulder 40 thus tends to rock the retainer toward operative position rather than camming it inwardly out of engagement with the shoulder, and it is also to be observed that the transverse arm 36 which carries the lip 39 is braced by its engagement with the walls of the cylinder recess in which it fits.

With the cylinder in its locked position of rotation, retraction of the bolt is positively prevented by a foot 46 formed on the bolt and engaging the side of the cylinder.

In its unlocked position, a recess 47 in the side of the cylinder aligns with the foot 46 to accommodate it and permit retraction of the bolt by inward depression of the cylinder in the normal manner.

If perchance the bolt spring 44 does not project the bolt to its operative position, turning of the cylinder to its locked position of rotation positively cams the bolt outwardly as the end 48 of the recess 47 rides under the foot 46.

From the foregoing description taken in connection with the accompanying drawings, it will

be readily apparent that this invention provides a lock device especially adapted for use on glove compartment doors which has substantial advantages over similar devices heretofore in use in that it positively secures the toggle bolt against retraction when the cylinder is in its locked position of rotation and simplifies the design of the lock mechanism by combining the tumbler spring retainer and the cylinder retainer.

What I claim as my invention is:

1. In a lock device of the character described: a casing having a bore open at its front end; and a lateral opening through the wall of the bore; a spring pressed toggle bolt pivoted in the casing with a part thereof inside the bore and a part thereof projectible through said lateral opening; a lock cylinder having limited axial and rotary motion in said bore and engageable upon inward depression to retract the projecting part of the bolt; a foot on the bolt positioned to collide with the side of the cylinder and positively prevent retraction of the bolt while the cylinder is in its locked position of rotation, said cylinder having a recess adapted to be aligned with said foot when the cylinder is turned to its unlocked position of rotation to accommodate the foot and free the bolt for retraction; and a cam surface at one side of the recess engageable with said foot as the cylinder is turned from unlocked to locked position to cam the bolt to its projected position in the event its biasing spring fails to do so.

2. In a latch for glove compartment doors and the like wherein a latch operating member is exposed at the front of the door through an opening in said door: a casing having its front end secured to the rear face of the door behind said door opening and having a bore opening to said front end to receive the latch operating member; a lock bolt having trunnions received in the bottoms of open-sided bearing sockets formed in the casing; a latch retainer engageable over the front end of the casing and confined between the rear face of the door and the casing; unitary means on the latch retainer projecting therefrom to overlie the lock bolt trunnions at the open sides of the bearing sockets for maintaining said trunnions at the bottom of their respective bearing sockets; and a pilot boss on the latch retainer entering the door opening from the rear of the door to lie between an edge portion of the door opening and the side of the latch operating member.

3. In a latch for glove compartment doors and the like wherein a latch operating member is exposed at the front of the door through an opening therein: a casing having its front end secured to the rear face of the door behind said opening and having a bore opening to said front end to receive the latch operating member; a lock bolt actuated by said latch operating member having trunnions received in the bottoms of open-sided bearing sockets formed in the casing; a latch retainer secured over the front end of the casing and having arms projecting therefrom to overlie the trunnions at the open sides of their bearing sockets for maintaining the same pivotally seated therein; and a pilot boss on the latch retainer entering the door opening from the rear of the door to lie between an edge portion of the door opening and the side of the latch operating member.
